188,616

PLATE OR SIMILAR ARTICLE

Gerald S. Stone, Scarsdale, N.Y., assignor to Johnson Bros. (Hanley) Limited, Hanley Pottery, Hanley, Stone-on-Trent, Great Britain, a British company

Filed Feb. 25, 1960, Ser. No. 59,524

Term of patent 14 years

(Cl. D44—15)

The figure is a top plan view of a plate or similar article of conventional configuration, showing my new design.

I claim:

The ornamental design for a plate or similar article, substantially as shown and described.

References Cited in the file of this patent UNITED STATES PATENTS

D. 165,855 Miller et al. _____ Feb. 5, 1952
OTHER REFERENCES

Crocker and Glass Journal, December 1955, page 14, plate labeled "K."